UNITED STATES PATENT OFFICE

123,070

DESIGN FOR A HEADLIGHT TESTING MACHINE

Henry Wochner, Rock Island, Ill., assignor to
Bear Manufacturing Company, Rock Island,
Ill.

Application December 4, 1939, Serial No. 88,663

Term of patent 14 years

To all whom it may concern:

Be it known that I, Henry Wochner, a citizen of the United States, residing at Rock Island, in the county of Rock Island and State of Illinois, have invented a new, original, and ornamental Design for Headlight Testing Machines, of which the following is a specification, reference being had to the accompanying drawing, forming part thereof.

In the drawing:

Fig. 1 is a front elevation of a headlight testing machine, showing my new design.

Fig. 2 shows the same in side elevation.

Fig. 3 is a plan view thereof.

A view from the other side of the machine would be substantially similar to that shown in Fig. 2.

I claim:

The ornamental design for a headlight testing machine, as shown and described.

HENRY WOCHNER.
